UNITED STATES PATENT OFFICE.

LEVI D. VAN VALKENBURG, OF HOLYOKE, MASSACHUSETTS.

FILTER.

1,041,915.

Specification of Letters Patent

Patented Oct. 22, 1912.

Application filed January 18, 1912. Serial No. 671,904.

To all whom it may concern:

Be it known that I, LEVI D. VAN VALKENBURG, a citizen of the United States of America, and resident of Holyoke, in the county of Hampden and State of Massachusetts, have invented certain new and useful Improvements in Filters, of which the following is a full, clear, and exact description.

10 This invention relates to improvements in small filtering devices of a kind which are adapted for a screw connection with a faucet.

15 An object of the invention is to provide improved means of construction whereby an efficient filtering device may be produced by simple and inexpensive construction.

20 Another object is to provide means, operative externally of the filter, whereby the screen-frame which constitutes the filtering medium in the device may be overturned for half of a revolution so as to be self clearing of sediment or impurities collected thereon.

25 Another object is to provide means whereby in the semi-revolvble movements of the screen-frame the latter will be held in its position squarely across the passage through the filter body.

30 Another object is to so construct and combine the parts that leakage of water is prevented through the sides of the body or the points penetrated by the transverse rotative shaft on which the screen-frame is mounted.

35 And other objects are attained in and by the special construction of the device and parts thereof as will hereinafter be rendered apparent.

40 The invention is described in conjunction with the accompanying drawings and is set forth in the claims.

45 In the drawings:—Figures 1 and 2 are central vertical sections of the filter on an enlarged scale as taken on planes at right angles to each other; these views showing reversals of the position of the screen-frame. Fig. 3 is an elevation at the side of the filter at which the screen operating handle is located. Fig. 4 is a horizontal cross sectional view on line 4—4, Fig. 2. Fig. 5 is a still

further enlarged sectional view showing the construction of the screen frame.

Similar characters of reference indicate corresponding parts in all of the views.

In the drawings, A represents the filter 55 body which is made of tubular form, internally screw threaded at its upper end and having the opening thereof somewhat contracted to form an approved delivery nozzle.

B represents the screen frame, and C the 60 shaft by which it is carried, and which shaft is transversely journaled through an intermediate portion of the tubular body. The said shaft for almost the entire length thereof is of a square or equivalent polygonal 65 form, and the holes a a through the opposite sides of the tubular body are round and of diameter sufficient to permit of the rotation of the shaft in its bearings there-through.

70 The screen frame which performs the filtering of the water passing through the device consists of a ring b made with a seat or ledge d and with an integral portion having its location outwardly beyond the ledge 75 formed thinner than the ring proper to produce an annular lip f; and the screen or gauze g resting on the ledge and confined thereon by angularly turning the lip as clearly shown in Fig. 5. The ring of the 80 screen frame has diametrically opposite square holes h h therethrough, through which the square shaft is engaged.

85 The holes a a in the opposite sides of the body are surrounded at their outer ends by countersunk depressions i i in which polygonally apertured disks j j are set, said disks being penetrated by portions of the shaft C which closely fit through them, so that while such disks form closures against leakage through the opposite shaft bearing holes a a, they rotate as one with the shaft and prevent no obstruction to the movements of the latter.

90 The shaft has a handle member D at one end, the inner portion of which,—that lying in proximity to the side of the filter body,—is of the form of a blade or fin and the portion of the filter body next outside of the disk j has a depression or niche k which is 100

radial to the axis of the handle provided shaft, so that the inner blade like edge of the shaft handle may have a detent engagement therein for preventing the tilting of 5 the screen frame away from its position as a filtering partition squarely across the passage through the filter body, excepting when the shaft is purposely rocked through means of the handle. The shaft on its end 10 opposite the handle has screw threads cut thereon with which engages a bonnet or knob F made with a chamber m opening to its inner end while within the wall closing its outer end is a screw tapped socket 15 of smaller diameter than the chamber, and leading endwise from the latter. A helical spring t encircles the end portion of the shaft and is inclosed, practically concealed and held in compression by the chambered 20 screw knob or bonnet. As the construction is viewed in Fig. 2, the spring reacting on the shaft in a direction to the leftward forces the blade shaped handle firmly against the right hand disk j, keeping the latter 25 closely seated in the depression i therefor, such spring force being also effective for maintaining the inner blade like portion of the handle engaged in the shallow radial niche k; and the spring in its direct reaction 30 against the little left hand disk holds that one closely seated in the circular depression therefor. The construction is such that a slight endwise movement of the shaft is permitted diametrically of the filter body, 35 and relatively to the screen frame when the shaft is to be rotated for overturning the screen frame so that the disengagement of the inner edge portion of the handle in the radial niche is permitted.

40 Although the circular holes a a through the opposite sides of the filter body are not entirely filled by the portions of the squared shaft which pass therethrough, the disks j j having the square openings tightly fitted 45 by the shaft constitute ample means of closure against the passage of water laterally from the filter body passage. And as may be perceived, the entire device is constituted by seven parts, all of which are of 50 extremely simple form and susceptible of production at low cost, and easy of assemblage,—the seven parts consisting of the tubular filter body, the strainer frame, the shaft, the pair of polygonally apertured 55 disks, the spring and the bonnet.

I claim:

1. In a device of the character described, in combination, a tubular body having diametrically opposed axially horizontal journal holes therethrough with countersunk depressions at their outer ends, a screen frame within the body having aligned polygonal openings therethrough, a polygonal

shaft engaged through the screen frame, polygonally apertured disks through which 65 the shaft is engaged and which are disposed in said circular depressions,—the said shaft having a handle enlargement at one end in engagement against one of the disks, and means operative on the shaft for holding it with its handle member in engagement with one of said disks. 70

2. In a device of the character described, in combination, a tubular body having diametrically opposed axially horizontal journal holes therethrough with countersunk depressions at their outer ends, and having a further depression radially relatively to one of the countersunk depressions, a polygonal shaft and a screen frame having openings corresponding to the cross sectional shape of the shaft and through which the latter is engaged, polygonally apertured disks through which the shaft is engaged and which are disposed in said circular 80 depressions,—the said shaft having a handle at one end made with a blade shaped portion for engagement in said radial depression and a spring exerting an endwise force to the shaft for yieldingly maintaining the 85 blade-like portion of the handle in said depression.

3. In a device of the character described, a tubular body having diametrically opposed journal holes therethrough and a depression adjacent and radial to one of said holes on the outer side of the body, a shaft extending transversely of the body through said holes having at one end a handle provided with a blade-like portion for engagement in said radial depression and having its opposite end screw threaded, a screen frame within the casing mounted on said shaft, an internally chambered bonnet engaging on the threaded extremity of the 100 shaft and having a spring inclosed and in reaction therein between the side of the casing and the wall of the chamber in such bonnet.

4. In a device of the character described, 110 a tubular body constructed for attachment on a faucet, a shaft transversely rotatively mounted in the body and a screen frame carried by said shaft within the casing and consisting of a ring made with a seat or 115 ledge and an integral portion of such ring outwardly beyond such ledge formed thinner than the ring proper to produce an annular lip, a screen resting on said ledge and confined thereon by the angularly turning of said lip, and means externally of the casing for rotatively moving said shaft.

5. In a device of the character described, in combination, a tubular body constructed for attachment on a faucet, a shaft, transversely and rotatively journaled through an 125

intermediate portion of the body, carrying
a screen-frame therein and having at one
of its extremities a shoulder in sidewise en-
gagement against the body, and a handle
5 member adjacent the body, provided at its
other end with spring means for drawing
the shoulder against the body, and detach-
able means for preventing the disengage-

ment of the shaft from the screen frame and
from the body.

Signed by me at Springfield, Mass., in
